SOLE FOR SHOES, SLIPPERS, OR OTHER ARTICLES OF FOOTWEAR

Filed March 29, 1944

UNITED STATES PATENT OFFICE

2,408,736

SOLE FOR SHOES, SLIPPERS, OR OTHER
ARTICLES OF FOOTWEAR

George Codish, New York, N. Y.

Application March 29, 1944, Serial No. 528,563

7 Claims. (Cl. 36—30)

1

This invention relates to soles for shoes, slippers, or other articles of footwear. It is particularly directed to a sole provided with a rope outsole.

Heretofore in making soles of rope or braid or the like wound element, difficulty was experienced because in winding the sole, it was not possible to completely fill in the ball portion. In accordance with the present invention this difficulty is obviated by making the outsole of wound cord or 10 rope, so wound as to leave an opening at the ball of the sole, an insert being provided at the ball to fill in the opening.

Another object of this invention is to provide a sole of the character described in which the rope is stitched longitudinally to a layer of sole material thereby producing a highly efficient and economical sole.

Yet another object of this invention is to provide in a sole of the character described, an insert comprising a filler and an ornamental covering for the filler, the edges of which are tucked beneath the wound cord or rope and said cord being stitched through the edges of the covering for the filler.

Yet another object of this invention is to provide a sole of the character described comprising a top layer, a rope outsole stitched to the underside of said layer, and an insert at the ball of the outsole, and a binding edge being provided for said top layer.

Yet a further object of this invention is to provide a strong, rugged and durable sole of the character described, which shall be relatively inexpensive to manufacture, which may be used with a wide variety of shoes or slippers, and which shall be practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a bottom plan view of a sole embodying the invention;

Fig. 2 is a top plan view thereof;

Fig. 3 is a cross-sectional view taken on line 3—3 of Fig. 2; and

2

Fig. 4 is a cross-sectional view taken on line 4—4 of Fig. 2.

Referring now in detail to the drawing, 10 designates a sole embodying the invention. The same comprises a top layer or board 11 made of any suitable sole material such as felt, fiber board, "Onco" or the like suitable material. Stitched all around the edge of the layer 11 is a binding 12 which may be made of cloth or imitation leather and of any color to enhance the appearance of the sole. The binding 12 extends entirely around the edge of the top layer and is stitched thereto by a line of stitching 12a.

At the underside of the layer 11 is an outsole 14. The same comprises a portion 15 made of wound cord or rope 17 of cotton, jute, sisal, manila, treated paper, cord, rope or the like flexible elements. The same is wound around the outer edge of the layer 11 and then continuously inwardly until the heel portion or rear of said layer is completely covered, leaving a central opening 20 at the ball of the sole which is uncovered by cord 17. The cord 17 is attached to the layer 11 by means of stitching 21 which runs lengthwise of the cord, the stitching extending through the cord and through the platform. The cord 17 may be cemented or otherwise adhered to the sole by any suitable adhesive instead of being attached thereto by stitching 21.

To fill the opening 20, there is provided an insert 25. Said insert comprises a filler member 26, of canvas, paper card board or the like material. The outline of filler 26 is somewhat smaller than the outline of the opening 20. To cover the filler 26 is a covering 27 made of canvas, leather, jute, fabric or any other material which may be coated to give it an ornamental appearance. The covering may be made of imitation leather or any other suitable material. The outer edges 27a of the covering member 27 extend beneath the outsole portion 15 and the same is stitched thereto by means of the stitching 21.

The filler 26 is preferably pasted or adhered to the underside of the platform 11 as at 26a. The combined thickness of the filler or covering member 27 is preferably substantially equal to the thickness of the cord 17.

It will be noted that the outer convolution of the cord 17 overlies a portion of the binding 12. It will thus be seen that there is provided a device in which the several objects of this invention are achieved, and which is well adapted to meet the conditions of practical use.

As various possible embodiments might be made 55 of the above invention, and as various changes

might be made in the embodiment above set forth, it is to be understood that all material herein set forth or shown in the accompanying drawing is to be interpreted as illustrative and not in a limiting sense.

Having thus described my invention, I claim as new and desire to secure by Letters Patent:

1. A sole comprising a sole shaped board, a cord contacting the underside of the board and wound continuously around one face of the board and covering all but the central portion of the ball of said board, and being stitched to said board by stitching extending longitudinally of the cord, and an insert at said central portion of the ball of the board, said insert comprising a filler contacting the underside of said board and disposed within said central portion of the ball of the board, and a covering for said filler, the edge portion of said cover being tucked beneath the wound cord and stitched to the board by the stitching which stitches the cord to said board.

2. A sole comprising a sole shaped board, a cord at the underside of the board wound continuously around one face of the board, with adjacent turns of the cord substantially contacting, said cord being stitched longitudinally to said board, the cord covering the heel of the board but exposing part of the ball of the board, and forming an opening surrounded by wound cord, and an insert within said opening attached to the board, said insert comprising a filler sheet adhered to the underside of the board and located wholly within said opening, and a flexible covering covering the underside of said filler, the edge of said flexible cover being disposed between the wound cord and said board and being stitched to the board by the stitching which attaches the cord to the board.

3. A sole comprising a sole shaped board, a cord at the underside of the board wound continuously around one face of the board and extending to the outer edge of the board, with adjacent turns of the cord substantially contacting, said cord being stitched longitudinally to said board, the cord covering the heel of the board but exposing part of the ball of the board, and forming an opening surrounded by wound cord, and an insert within said opening attached to the board, and a binding around the edge of the board, part of the binding being disposed between part of the wound cord and the board and being stitched to the board by the stitching which stitches the cord to the board.

4. A sole comprising a sole shaped board, a cord contacting the underside of the board and wound continuously around one face of the board and covering all but the central portion of the ball of said board, and being stitched to said

board by stitching extending longitudinally of the cord, and an insert at said central portion of the ball of the board, said insert comprising a filler contacting the underside of said board and disposed within said central portion of the ball of the board, and a covering for said filler.

5. A sole comprising a sole shaped board, a cord at the underside of the board wound continuously around one face of the board, with adjacent turns of the cord substantially contacting, said cord being stitched longitudinally to said board, the cord covering the heel of the board but exposing part of the ball of the board, and forming an opening surrounded by wound cord, and an insert within said opening attached to the board, said insert comprising a filler sheet adhered to the underside of the board and located wholly within said opening, and a flexible covering the underside of said filler.

20 6. A sole comprising a sole shaped board, a cord at the underside of the board wound continuously around one face of the board, with adjacent turns of the cord substantially contacting, said cord being stitched longitudinally to said

25 board, the cord covering the heel of the board but exposing part of the ball of the board, and forming an opening surrounded by wound cord, and an insert within said opening attached to the board, said insert comprising a filler sheet adhered to the underside of the board and located wholly within said opening, and a flexible covering covering the underside of said filler, the edge of said flexible cover being disposed between the wound cord and said board and being stitched to the board by the stitching which attaches the cord to the board, and a binding around the edge of the board, part of the binding being disposed between part of the wound cord and the board and part of the binding overlying the opposite

30 35 40 face of the board, said binding being stitched to the board by the stitching which stitches the cord to the board.

7. A sole comprising a sole shaped board, a cord wound continuously around the underside of the board, and extending to the outer edge of said board with adjacent turns of the cord substantially contacting, said cord being stitched longitudinally to said board, and a binding around the edge of the board, part of the binding being disposed between the wound cord and the underside of the board, and part of the binding overlying the upper face of the board, the parts of the binding contacting the underside of the board and the upper face of the board being stitched to the board by the stitching which stitches the cord to said board.

GEORGE CODISH.
